UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

DOOR-OPERATING MECHANISM.

1,317,775.

Specification of Letters Patent.

Patented Oct. 7, 1919.

Application filed January 23, 1919. Serial No. 272,621.

To all whom it may concern:

Be it known that I, ARGYLE CAMPBELL, a citizen of the United States, residing at Chicago, in the county of Cook and State of Illinois, have invented a certain new and useful Improvement in Door-Operating Mechanisms, of which the following is a full, clear, concise, and exact description, reference being had to the accompanying drawings, forming a part of this specification.

This invention relates to improvements in door operating mechanisms.

One object of the invention is to provide a simple and efficient mechanism for opening and closing pivoted doors and more particularly pivoted doors of dump cars.

Another object of the invention is to provide a door operating mechanism more particularly adapted for dump car doors and wherein means are provided for positively opening the doors and maintaining the latter in open position.

Still another object of the invention is to provide a mechanism of the character above described, wherein tendency of the load on the doors to turn the shaft in an opening direction is eliminated.

In the drawings forming a part of this specification, Figure 1 is a broken view of a portion of a hopper dump car showing my improvements in connection therewith. The view is that of the central portion of a car, the right hand portion of the figure being in side elevation and the left hand portion in vertical, longitudinal section. In the elevational part of the view, the hopper doors are shown in closed position and in the sectional part of the view the doors are shown in open position. Fig. 2 is a vertical, transverse, sectional view of the dump car shown in Fig. 1, the section corresponding substantially to the line 2-2 of said figure. In Fig. 2 parts of the car are broken away in order to prevent crowding of the drawing. Fig. 3 is an enlarged view partly in elevation, partly in vertical section illustrating more particularly the details of the door operating mechanism, the parts being shown with the door in closed position. Fig. 4 is a top plan view of the door operating mechanism proper shown in Fig. 3. Fig. 5 is a detail perspective of one of the drums employed in my construction. Fig. 6 is a detailed perspective view of the terminal link

employed in my construction. And Fig. 7 is a top plan view, detached, of the supporting or connecting link for the door.

In said drawings, I have illustrated my improved mechanism as applied to a well known form of hopper dump car wherein the car is provided with four hoppers extending downwardly and from the ends of the car toward the center thereof, two on each side of the center sills, the hoppers being arranged in pairs as will be evident. Each of the hoppers is provided with a hopper bottom sheet indicated at 10, a door opening indicated at 11 and a hopper door indicated at 12, the hopper doors 12 being pivoted along their top edges as shown in Fig. 1. The doors 12 of each set transversely of the car are preferably operated simultaneously and for this purpose each set is connected by a cross bar indicated at 13 in Fig. 2. The car is shown as provided with a center sill of usual construction, the same comprising a pair of channels 14-14, cover-plate 15 and an apex load-shedding plate 16.

For each pair of doors 12 I provide an operating mechanism, the same comprising, broadly, a transversely extending operating shaft A, a drum B, a terminal link C, and a hook-shaped supporting or connecting link D.

Each shaft A extends transversely of the car beneath the corresponding hopper bottom sheets 10 and to support the shaft, suitable bearing brackets 17-17 are provided secured to the under sides of the hopper sheets and to the inner longitudinally extending side hopper sheets 18. The shafts are provided at their ends with ratchet wheels 19, pivoted locking dogs 20 and pivoted cams 21 to hold the dogs 20 against accidental disengagement, as will be seen from an inspection of Fig. 1. The shaft is rotated in any suitable manner as by a claw bar, as will be understood.

The drum B, shown most clearly in Figs. 3, 4 and 5, is mounted on its corresponding shaft A at the center of the latter and directly beneath the center sill as shown in Fig. 2. Each drum B comprises a sleeve section 22, a link connecting lever arm 23, a bearing arm 24 and a kick-off cam 25. The sleeve 22 is axially cored or recessed so as to slip over the shaft A, the recess being preferably square and the shaft square as shown in Fig. 3 so as to insure rotation of

the drum B in unison with the shaft. Referring to the construction as illustrated in Fig. 3, where the parts are in the position assumed with the door closed, the lever arm 23 extends downwardly and at an angle to the vertical in a direction toward the door 12. At its lower end, said lever arm 23 is perforated as indicated at 26 to receive a pivot pin 27 by which the corresponding forked ends of the terminal link C are connected thereto. It will also be noted from an inspection of Fig. 3 that the arm 23 is provided with an integral relatively wide flange 28 which overlaps the adjacent end of the link C and which engages the upper side of the latter as indicated at 29 in Fig. 1 when the mechanism is in the position assumed with the door in open position. As will be obvious, this prevents the link C from swinging upwardly about its pivot pin 27 as the parts are shown in Fig. 1 and the reason for this will appear hereinafter.

The bearing arm 24 of the drum B extends substantially horizontally as viewed in Fig. 3 and at its outer or right-hand end is formed with a vertical flat bearing face 30 which is adapted to engage a corresponding flat bearing face 31 on the other end of said link C, when the door is in closed position.

It will also be noted from an inspection of Fig. 3 that the arm 24 is provided at its said outer end with inwardly inclined faces 32-33 on each side thereof and with an outwardly extended lug 33. Said lug 33 is tapered at its lower end as indicated at 34. The lug 33 is adapted to enter a corresponding opening 35 in the link C when the parts assume the position shown in Fig. 3, and it will be evident that this interengagement of the lug 33 with the link C serves to positively position the link C when the parts are approaching the position shown in Fig. 3 and will positively prevent any lateral movement of the link C with respect to the bearing arm 24. The lug 33 also performs another important function in that it will engage the upper shoulder 36 of the link C during the unwinding movement in the event the door should be stuck for any reason, such as freezing of the load, and thereby positively force the link C in its unwinding action simultaneously and uniformly with the movement of the shaft and hub.

Said link C adjacent its bearing face 31 is provided with a pair of perforated ears 36-38, straddling the end 37 of the supporting or connecting link D, said end 37 being also perforated and the two links being pivotally connected as by a pin 38. The link D is of substantially hook-shape as clearly appears from Figs. 1 and 3. At its end remote from its pivotal connection to the link C, the link D is pivotally connected to the doors 12-13 by means of an eye bolt 40 and pivot pin 41, said end of the link D being forked

to straddle the bolt 40 as indicated at 39-40. The eye bolt 40 is mounted between the channels 41-41 forming the cross bar 13 and extended through a cover-plate 412 and is adjustable within as by means of the nuts 70 and lock nuts 42-42.

As shown in Figs. 3, 4 and 7, the link D is provided on one side thereof with a beveled shoulder 43 in the same plane as the kick-off cam 25. The periphery 44 of said cam 25 is eccentric with respect to the center of the shaft A and is adapted to engage said shoulder 43 during the unwinding or opening movement of the mechanism so as to positively force said link D and thereby the corresponding doors 12 to an open position. The kick-off cam 25 in combination with the lug 33 obviously will insure the positive opening of the doors even though the latter are frozen.

85

Referring again to the link C, it will be noted that the same is provided with a shoulder 45 adjacent the perforated ears 36, which shoulder 45 is adapted to engage the end 37 of the link D when the doors are in open position, as indicated at 46 in Fig. 1. By engaging the link C with the lever arm 23 as indicated at 29 in Fig. 1 and by engaging the link C with the link D as indicated at 46 in Fig. 1, it is evident that the doors 95 will be positively held in open position and prevented from swinging when the car is in transit, so long as the shaft A is in its position assumed when the doors are open. It will also be observed that a line extending 100 between the pivot pins 38 and 41 will pass below the center of the shaft 14, as viewed in Fig. 3, so that the load on the door will be transmitted through the link C to the bearing arm 24 of the drum B 105 in such manner as to positively eliminate any tendency of the load to turn the shaft 14 in an opening direction.

With the construction above described, the drum and links C and D may be made in 110 the form of castings and the drum B is especially light since all metal not actually required in carrying out the function of the drum, is eliminated.

115

I claim:

1. In an operating mechanism of the character described for pivoted doors, the combination with a rotatable shaft having a drum thereon provided with a radially extending arm having a flat bearing face disposed on the opposite side of the shaft to that of the door when the door is in closed position, of a link pivotally connected at one end of the drum at a point remote from said bearing face and having also a flat 120 portion adapted to lie against said flat bearing face when the door is in closed position, and a supporting connection pivotally connected at one of its ends to the door and at its opposite end to the other end of said 125 link.
2. In an operating mechanism of the character described for pivoted doors, the combination with a rotatable shaft having a drum thereon provided with a radially extending arm having a flat bearing face disposed on the opposite side of the shaft to that of the door when the door is in closed position, of a link pivotally connected at one end of the drum at a point remote from said bearing face and having also a flat 130 portion adapted to lie against said flat bearing face when the door is in closed position, and a supporting connection pivotally connected at one of its ends to the door and at its opposite end to the other end of said link.

link, the load on the door being transferred to the drum through said link.

2. In an operating mechanism of the character described for pivoted doors, the combination with a rotatable shaft having a drum thereon provided with a bearing face, of a link pivotally connected at one of its ends to said drum and having also a bearing face adapted to lie against said bearing face of the drum when the door is in closed position, a connecting link pivotally attached at one end to the door and at its opposite end to the other end of said first named link, and coöperating means on said connecting link and said drum adapted to positively force said connecting link in a direction toward the door when the shaft is rotated in a direction to open the door.

3. In an operating mechanism of the character described for pivoted doors, the combination with a rotatable shaft having a drum thereon, said drum being provided with an integral lever arm and an integral bearing arm disposed at an angle to each other and both extending radially from the drum, said bearing arm having a bearing face disposed on the opposite side of the shaft to that of the door when the door is in closed position, a link pivotally connected at one of its ends to said lever arm, said link having a bearing face adjacent its other end adapted to lie against said bearing face of the bearing arm of the drum when the door is in closed position, and a supporting connection pivotally connected at one of its ends to the door and at its opposite end to said link adjacent said bearing faces, load from the door bearing transmitted to the shaft through said bearing faces.

4. In operating mechanism of the character described for pivoted doors, the combination with a rotatable shaft having a drum thereon, of a link pivotally connected to said drum and adapted to lie thereagainst when the door is in closed position, supporting means between said link and the door, and coöperating engaging means on the drum and link to hold the latter positively in place against lateral displacement when the door is in closed position, said means coöperating to positively force said link in unison with the shaft in an unwinding direction when the shaft is rotated to open the door.

5. In an operating mechanism of the character described for pivoted doors, the combination with a rotatable shaft having a drum thereon provided with a bearing face, of a link pivotally connected at one of its ends to said drum and having a bearing face adapted to coöperate with the bearing face of the drum when the door is in closed position, a connecting link between said first named link and the door, coöperating means on said connecting link and the drum adapt-

ed to positively force the connecting link in a direction toward the door when the shaft is rotated to open the door, coöperating shoulders on the first named link and the drum, and coöperating shoulders on the first named link and the connecting link, said sets of coöperating shoulders acting to prevent collapse of the link connections between the drum and door when the latter has been moved to its open position.

6. In an operating mechanism for pivoted doors of a hopper car, the combination with a rotatable shaft mounted on the car and extending parallel to the pivotal connection of the door, of a drum rotatable in unison with said shaft, said drum having a lever arm, a bearing arm and a kick-off cam formed integrally therewith, of a terminal link pivotally connected at one end to said lever arm, a connecting link pivotally connected at one of its ends to the opposite end of said terminal link, said connecting link being pivotally connected at its opposite end to the door, coöperating bearing shoulders on the bearing arm of the drum and said terminal link through which the load from the door is adapted to be transmitted to the shaft when the door is in closed position, coöperating means on said bearing arm and terminal link arranged to positively position the latter with respect to the bearing arm when the parts are in closed position, a shoulder on said connecting link coöperable with said cam arm, and coöperating sets of shoulders on the lever arm and terminal link and on the terminal link and connecting link adapted to hold the link connections against collapse when the door is in open position.

7. In an operating mechanism of the character described for pivoted doors, the combination with a rotatable shaft having a drum thereon, said drum having a bearing arm provided with a projecting shoulder, of a link pivotally connected at one of its ends to said drum and adapted to bear against said bearing arm and provided also with a shoulder coöperable with said projection, and a door supporting connection extending between the other end of said link and the door, said projection and shoulders coöperating during the opening movement of the mechanism to positively insure uniform and simultaneous movement of said link with the drum.

8. In an operating mechanism of the character described for opening doors, the combination with a rotatable shaft having a drum thereon, of a link pivotally attached at one of its ends to said drum, a link pivotally attached at one of its ends to the opposite end of said first named link and at its other end to the door, coöperating means on the second named link and the drum adapted to positively force said second named link in a
